(57) **CLAIM**

The ornamental design for a fluid coupling as shown and described.

DESCRIPTION

FIG. 1 is a top and front perspective view of a fluid coupling; FIG. 2 is a front elevation view thereof; FIG. 3 is a rear elevation view thereof; FIG. 4 is a first side view thereof; FIG. 5 is a left-side view thereof; FIG. 6 is a top plan view thereof; FIG. 7 is a bottom plan view thereof; and, FIG. 8 is a top and rear perspective view thereof.

The evenly spaced broken lines and unshaded areas depict portions of the fluid coupling that form no part of the claimed design. The long dash dot broken lines depict unclaimed portions of the fluid coupling and also denote the boundaries of the claim and form no part of the claimed design.

1 Claim, 6 Drawing Sheets
